US00D838198S

(12) **United States Design Patent** (10) Patent No.: **US D838,198 S**
(45) Date of Patent: **** Jan. 15, 2019**

(54) **GAS CHROMATOGRAPH ANALYZER**

(71) Applicant: **SHIMADZU CORPORATION**, Kyoto (JP)

(72) Inventor: **Jun Kimura**, Yawata (JP)

(73) Assignee: **SHIMADZU CORPORATION**, Kyoto (JP)

(**) Term: **15 Years**

(21) Appl. No.: **29/611,696**

(22) Filed: **Jul. 25, 2017**

(30) **Foreign Application Priority Data**

(57) **CLAIM**

The ornamental design for a gas chromatograph analyzer, as shown.

DESCRIPTION

FIG. 1 is a perspective view of a gas chromatograph analyzer showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
